FURNACE SEAL MEANS

Willard Albertsen and David Cope, Salem, and Ralph J. Perrine, Columbiana, Ohio, assignors to The Electric Furnace Company, Salem, Ohio, a corporation of Ohio
Continuation of application Ser. No. 249,835, Jan. 7, 1963. This application May 5, 1965, Ser. No. 456,035
23 Claims. (Cl. 266—3)

This invention relates in general to a furnace for continuous thermal treatment of metallic strip materials, wherein the strip enters the furnace and progresses at a substantially constant rate therethrough until thermal treatment has been completed, whereinafter the strip continues without interruption through the furnace exit means for recoiling or the like.

This application is a continuation of and has co-pendency with our parent application, Serial No. 249,835, filed January 7, 1963, now abandoned.

In particular the invention relates to improved entrance and exit seals required on furnaces adapted for continuous thermal treatment of metallic strip in which the treatment is conducted in a controlled protective atmosphere such as substantially pure hydrogen or dissociated ammonia.

It is therefore among the objects of this invention to provide improvements in furnace seal means which: prevent inward flow and diffusion of air from the surrounding atmosphere into the furnace; allow appreciable internal pressure to be maintained in the furnace without excessive loss of protective atmosphere gas; avoid damage to the metallic strip by abrasion or other action to the surfaces thereof; accommodate irregularities in the metallic strip, such as splices between successive coils, rough edges, and other irregularities with only a minimum and brief increase in furnace atmosphere outflow; avoid damage to the sealing means caused by strip irregularities; permit replacement of worn or accidentally damaged parts without requiring that the furnace be taken out of operation for a period greater than actually required to make the immediate repairs; handle strip of various widths and thicknesses without requiring special adjustments; tolerate strip which departs considerably from flatness in a transverse section; control movement of strip from entrance seal to exit seal to prevent misalignment of the strip within the furnace; and require very slight tension to advance the strip through the entrance and exit seals.

Seal means of many kinds are known in the prior art for use in conjunction with a so-called "strip annealing furnace," and such means include, among others, curtains of felt, asbestos cloth, and glass cloth. These means are sometimes employed as "wipers" and are held in contact with the work strip by mechanical pressure. Seals including metal rollers have also been attempted.

Experience has shown, however, that curtain or wiper type seals rapidly become ineffective because they are damaged by defects in the work strip, such as ragged edges, slivers, splices and so forth. Additionally, detached slivers may become lodged in the curtains or wipers, and thereafter may scratch or otherwise damage the surface of the strip. In like manner, seals with metal rollers fail to provide adequate sealing, and also tend to scratch the surfaces of the work strip.

It is a further object of our invention, therefore, to provide a roller seal having non-metallic contact with the work strip, which is not easily damaged, and is capable of easy repair as required.

The features of this invention, which are believed to be novel, are set forth with particularity in the appended claims. The invention itself, however, both as to its organization and use, together with further objects and advantage thereof, may best be understood by reference

2

to the following description taken in conjunction with the accompanying drawings, in which:

FIGURE 1 is a sectional elevation of a preferred embodiment of the invention taken on the line 1—1 of FIGURE 3;

FIGURE 2 is an elevational view of the preferred embodiment of the invention shown in FIGURE 1 taken along the line 2—2 of FIGURE 3;

FIGURE 3 is a sectional fragmentary elevation of the preferred embodiment of the invention taken along the line 3—3 of FIGURE 1;

FIGURE 4 is a perspective exploded view of one of the roll seal means employed in the invention, and shown in association with end sealing means;

FIGURE 4A is a fragmentary perspective view of wiping means used in association with the roll seal means of FIGURE 4;

FIGURE 4B is a fragmentary perspective view of another embodiment of wiping means used in association with the roll seal means of FIGURE 4;

FIGURE 5 is another embodiment of the invention shown in sectional elevation and taken on the line 5—5 of FIGURE 7;

FIGURE 7 is a fragmentary sectional elevation of the embodiment of the invention shown in FIGURES 5 and 6 taken on the line 7—7 of FIGURE 5;

FIGURE 8 is a sectional elevational view of still another embodiment of the invention for use in conjunction with horizontal strip furnaces;

FIGURE 9 is a fragmentary sectional plan view of the embodiment of the invention shown in FIGURE 8 taken on the line 8—8 of FIGURE 8;

FIGURE 10 is a fragmentary view of the ends of a pair of roll seal means in sealing engagement with the work strip;

FIGURE 11 is an elevational sectional view of an alternative form of leaf seal; and,

FIGURE 12 is a schematic control diagram of fluid pressure means to selectively operate each side of the roll seal.

Reference is now made to the drawings in greater detail, and in particular to FIGURES 1, 2 and 3 wherein is shown in seal roll housing 10, including vertical metal side plates 12 located outboard of the margins of the work strip W, and box forming angle members 14. The inner faces 16 of plates 12 are finished true and smooth, and are positioned accurately parallel. A passageway 18 formed by spacing angle members 14 is of sufficient size to provide clearance for the maximum expected strip widths and any possible irregularities in the direction of strip, thickness, such as splices, damaged edges, and so forth.

A pair of rolls 20 and 22 having metal cores 24 are provided with stub shafts 26 and outer coverings 28. The outer coverings 28 are provided to make contact with the work strip W at the pass line P of the furnace complex. These coverings are of rubber-like material, preferably having good wear resistance and toughness, and are capable of withstanding fairly high temperatures. Neoprene, silicone rubber, and other synthetic materials have proved satisfactory for this purpose. The neoprene covering has been found to provide best results having a "Shore Durometer A" hardness in the range of 50 to 65.

The ends 30 of the roll bodies are finished to planes at right angles to their axes of rotation, and the ends of the coverings 28 are also cut in alignment with these planes. Washers 32 of easily compressible rubber-like material are provided at each end 30 of the rolls in contact with the roll bodies 24 and with coverings 28.

(See also FIGURE 4.) In practice sponge neoprene of closed-cell type has been used. For rolls of the order of 6 inches diameter and 30 inch body length, washers 32 of approximately 0.5 inch uncompressed thickness have been successfully employed. A central opening 34 is provided in each washer 32 of diameter to fit snugly around stub shaft 26.

Outwardly of each washer 32 is a rubbing washer 36, usually about $\frac{1}{16}$ inch thickness and of diameter preferably slightly less than the roll covering 28. Material for these rubbing washers should have low coefficient of friction and low rate of wear when operated in rubbing contact with washers 32 or with a smooth metallic surface. Tetrafluoroethylene resins, such as manufactured under the trade name "Teflon," are well suited for this purpose. Metal seal washers 38, provided outwardly of rubbing washers 36, are of the same diameter as the rubbing washers 36, and are usually $\frac{1}{16}$ inch to $\frac{1}{8}$ inch in thickness. These metal seal washers 38 may be of carbon steel, stainless steel, or nonferrous metals such as bronze. Central openings in washers 36 and 38 are of a diameter to provide "running fits" on stub shafts 26. In certain applications, it is possible to omit rubbing washers 36 and use only sponge washers 32 and metal washers 38. In such cases relative rotation usually occurs between washers 38 and housing side plates 12. Suitable lubricant may be applied through slots 40 to minimize the rate of wear.

Stub shafts 26 are mounted in self-aligning bearings 42, attached to bell cranks 44 and 46, which are pivotally mounted on shafts 48. To maintain parallelism between the axes of rolls 20 and 22, corresponding bell cranks on opposite sides of the rolls may be connected by stiff tubular torsion members 50. A fluid motor 52 is attached to an extension ear 53 of each bell crank of at least one roll and may be used to urge the rolls toward each other or away from each other. To constrain the roll axes to be equidistant from the pass line P at all times, bell cranks 44 and 46 may be provided with gear sectors 54 and 56 in meshing engagement at 58. For ease of maintenance and repair, slots 40 and 41 are provided in each side plate 12 to facilitate quick removal of rolls 20 and 22. Also, slots 40 and 41 serve to permit shifting of rolls 20 and 22 toward and away from each other as is described with great particularity hereinafter.

In operation, the rolls 20 and 22 are urged toward each other with sufficient force to compress coverings 28 by a total amount slightly more than the thickness of the work strip W, so that coverings 28 are in contact under some pressure beyond the edges of the work strip W, which are thus enfolded thereby. As best shown in FIGURE 10, there is shown but a small triangular space 64 not sealed by the work rolls 20 and 22.

A difficulty sometimes encountered in handling continuous strip is that of imperfect "tracking." Thus, a work strip W may be well centered between side plates 12 of the entrance seal assembly 10, but if the work strip has an edgewise curvature, or "camber," one edge being slightly longer than the other, the work strip may be considerably off center when it reaches the exit end of the furnace. With the present invention, useful control may be exercised over strip tracking by applying more roll pressure to the strip at one edge than at the other. With stiff torsion members 50, it is not feasible to change the pressure distribution to a useful extent. However, by making one or both torsion bars relatively slender, as shown at 64' (FIGURE 1) rather than stiff tubular members 50, the bell cranks at one edge of the strip W may be displaced angularly relative to those of the other edge, with resulting differential pressures exerted on the strip at the opposite edges thereof. This operation causes the strip to change its position laterally to a useful extent, and thus, compensates for tracking error caused by a cambered strip.

In the embodiment of the invention shown in FIGURES

1, 2 and 3 a separate fluid motor 52 is shown for each bell crank. However, with gear teeth acting at 58, satisfactory operation can be had with a cylinder attached only to the pair of bell cranks on the same side of the strip. By varying the pressures in the cylinder or cylinders at one edge of the strip relative to the cylinder or cylinders at the opposite edge, and by providing yieldable spring torsion bars such as 64, the forces exerted by the rolls on the strip, and relative forces at the two edges, can be adjusted over a considerable range.

Various means for controlling air pressures may be resorted to, and an embodiment for illustrative purposes only is shown in FIGURE 12. A detailed discussion of FIGURE 12 will be undertaken hereinbelow following completion of the description of the seal means per se.

The seal assemblies described and discussed hereinabove provide for sealing between the work strip W and the rolls 20 and 22, and sealing between the roll ends 30 and the side plates 12. It still remains to provide further sealing means tangential to the rolls 20 and 22, the side plates 12, and the housing angle members 14. With the rolls 20 and 22 so encased, a complete seal is provided which accomplishes the objects enumerated hereinabove.

To this end, flexible leaves 66 (see also FIGURE 4A), are placed in tangential contact with the rolls 20 and 22, and are connected gastight to a transverse portion 68 of housing angles 14. Leaves 66 are provided with sealing material such as wool felt 70 on their under surfaces and at edges adjacent to the side plates 12. This sealing material 70 prevents or minimizes gas leakage therebetween, while permitting some movement of the leaves normal to the roll peripheries. Leaves 66 are made of sheet metal such as stainless steel, having a moderate spring temper. Each leaf is attached by fastening means 69 to flanges 72 of transverse housing member angles 14. The edges of leaves 66 nearest to the strip W are flanged upward, and the felt material 70 is attached to the flanges by clamp strip 74 and fastening means 76. At flange 72 a similar attachment is made.

In the entrance seal such as shown in FIGURE 1, the upper surfaces of rolls 20 and 22 move away from the strip and toward the leaves 66, tending to drag felt facing 70 away from the free edges of leaves 66 and thereby placing the felt facing in tension, thus requiring that the edges 78 of the facing 70 be securely fastened at the clamp strip 74 of the leaf 66. In the alternative, the facing 70 may be fastened permanently to the leaves 66 by an adhesive.

FIGURE 4A illustrates the relationship between the edge of leaf 66 and side plates 12 when the felt or equivalent material is used as a facing secured to the edges and underside of the leaf. An alternate arrangement is shown to the right thereof at FIGURE 4B wherein the facing 71 is secured by an adhesive to leaf 73 rather than clamping means employed with leaf 66. In any event, leaves 66 and 73 are slightly shorter, parallel to the pass line, than the distance between the plates 12. Facings 70 and 71 are cut so as to extend beyond leaves 66 and 73 respectively at 79 and 80 so as to rub against end plate surfaces 16 while permitting the leaves to be bent upward. Atmospheric leakage between side plates 12 and leaves 66 or 73 is thus kept very minimal.

Yet another alternative leaf construction is shown in FIGURE 11, wherein the leaf 82 is of solid metal and relatively thick. It rests by gravity at 84 on roll covering 28, and the leaf 82 is pivotally mounted on screw 86 extending through each side plate 12 into a socket 88 in leaf 82. Rear edge 90 of leaf 82 and adjacent surface 92 of member 14 are finished to cylindrical shape, concentric with screw 86. Packing grooves are formed in the side edge and rear edge surfaces of leaf 82 to receive packing 94. Surrounding the depression 88 a packing recess is partly circular, and packing strip 94 preferably is molded to fit in these recesses. The packing protrudes

far enough beyond the edge surfaces of leaf 82 to make sealing contact with surfaces 92 and 16 of the seal housing, while yet allowing pivotal motion about screws 86. The lower surfaces of solid leaves 82 may, if desired, be faced with yieldable materials such as wool felt, as is shown for leaves 66 in FIGURE 1, and preferably bonded to the leaf 66 as shown in FIGURE 4B. Also, a facing of "Teflon" may be used.

General reference is now made to FIGURES 5, 6 and 7, wherein is shown yet another embodiment of the invention, and, in particular, alternate means for shifting the rolls 20 and 22 into and out of a pressure engagement with the work strip W. In FIGURES 6 and 7, it will be observed that a fluid motor 100 is drivingly connected to a slide 102 by means of a screw 104 and nut 106, the screw being secured to the air motor, and the nut being secured to the slide, with gib 108 being provided to guide the slide for limited vertical movement. Each roll is journaled in a toggle plate 110 which is pivotally mounted at its lower inboard corner 112 to a housing side plate extension ear 113, and is pivotally connected at its upper end to the slide 102 by a toggle link 116. In order to maintain parallelism between the rolls 20 and 22, the toggle plates 110 on opposite ends of the rolls are connected by torsion tubes 118. Thus in order to separate the rolls, fluid motor 100 is actuated to drive the slide 102 downwardly, whereby the toggle links 116 urge the toggle plates 110 arcuately apart from the pass line of the seal. Conversely, to pressure engage the rolls, the fluid motor is reversed whereupon the slide 102 is urged upwardly, thereby placing the toggle links in tension, and arcuately pivoting toggle plates inwardly toward the pass line of the seal. Because of the arcuate movement of the rolls, arcuate slots 120 are provided in side plates 114 to receive stub shafts 122, and to accommodate arcuate movement thereof.

In view of the arcuate movement of the rolls 20 and 22, which is somewhat in excess of the arcuate movement of rolls shown in FIGURE 1, the sealing leaves 124 are inclined at about 30° to the horizontal engagement with the rolls during adjusting movement. Otherwise, the seal illustrated in FIGURES 5, 6 and 7 functions substantially in accordance with the operation of the seal disclosed in FIGURES 1, 2 and 3.

Reference is now made to FIGURES 8 and 9 which disclose an embodiment of seals for use with horizontal strip travel. The seal housing of this embodiment includes lower plate members 126, 128, 130 and upper plate 132, and side plates 134. Lower roll 136, with fixed axis, and upper roll 138, having its axis shiftable vertically, are located with axes in a transverse vertical plane, for pressure engagement one with the other, for pressure engagement with a strip passing therebetween in a horizontal plane. Each roll is provided with a set of end discs equivalent to the end discs illustrated in FIGURE 4. The elastomeric coverings 140 are also similar to the coverings for the rolls already discussed hereinabove. The stub shafts 26 of rolls 136 and 138 are mounted in takeup type self-aligning ball bearing units 142 fitted between guides 150, the two bearing units related to the lower roll 136 being seated fixedly, and those related to the upper roll 138 being movable upwardly from the position shown.

A connecting link 146 is pinned to each of the two bearing units 142 of upper roll 138. Each link 146 is also pinned to a lever 148, which is fulcrumed at 150 upon frame 152. Torsion bar 154 is attached between the two levers 148 and tends to hold roll 138 level, subject to such torsional deflection as may be permitted by the slenderness of bar 154. A fluid cylinder 156, attached to frame 152 at 158, is pinned to each lever 148. The force exerted by roll 138 upon roll 136 and work strip W depends upon the size of cylinders 156 and the fluid pressure imposed on the cylinders. By virtue of the torsional deflection of torsion bar 154, roll 138 may be

5

6

loaded more heavily at one side than the other if desired, as heretofore described relative to the embodiment of the invention shown in FIGURES 1, 2 and 3. The essential difference being that the embodiment in FIGURES 1, 2 and 3 is primarily suited for sealing the movement of vertical strip passing through the furnace, wherein both rolls may move away from the strip pass line. As already discussed, only the upper roll 138 moves in the embodiment shown in FIGURES 8 and 9. However, it will become readily apparent to those skilled in the art that with slight modification in the so-called vertical design, it can be adapted for horizontal furnaces.

As in the vertical seal, a closure is also required in the horizontal seal between each roll and the roll housing. For this purpose seal leaves 160 and 162 are provided with compressible facings 164. The leaves are clamped to housing flanges 166 and 168, and are spring urged into tangential contact with the rolls 136 and 138. For leaves of this type and position, force other than direct gravity may be required to insure adequate sealing, and in this event spring or counter weight means may be added to the natural resilience of the leaf springs themselves. For ease of maintenance, particularly with respect to the frequency of replacing felt covers 164, the entrance seal will have leaves 160 and 162 preferably located to the left or forward of the seal roll, whereas in the application for an exit seal it is preferable to mount the leaves on the right or extreme remote side of the seal rolls as shown in phantom.

Reference is now made to FIGURE 12, a schematic diagram illustrating in general the application of the actuating cylinders of the seal rolls in any of the arrangements shown in the drawings, and in particular with reference to FIGURE 1. Four cylinders, 52A, 52B, 52C and 52D, are shown in pairs with each pair acting adjacent an edge of the work strip W. As shown, pressure applied through lines 240A and 240B, will force the rolls 20 and 22 toward the strip W, and pressure applied through lines 241A and 241B, will separate the rolls.

More specifically, solenoid 4-way valve 243 is energized to allow pressure from the line 242A to enter line 242B and branch lines 243A and 243B. The check valves 244A and 244B close and the pressure passes through adjustable pressure regulators which may take the form of manually operated pressure regulators 246A and 246B. Check valves 247A and 247B open, the pressure by-passing throttle valves 248A and 248B. The pressure then enters cylinders 52 through lines 240A and 240B. Simultaneously air is exhausted through lines 241A and 241B, closing check valves 249A and 249B, and through throttle valves 251A and 251B to provide regulation of cylinder speed. The pressure then enters branch lines 252A and 252B, and thereafter is exhausted through line 253B and solenoid 243 to line 253A.

To separate the rolls 20 and 22, solenoid 243 is energized to apply pressure from line 242A through 4-way valve 243 and to line 253B. The pressure by-passes throttle valves 251A and 251B, opens checks 249A and 249B, and enters cylinders through lines 241A and 241B. Simultaneously air is exhausted from cylinders 52 through lines 240A and 240B, closing check valves 247A and 247B, and through throttle valves 248A and 248B. The exhausting fluid by-passes regulators 246A and 246B, opens check valves 244A and 244B to branch lines 243A and 243B, and then enters manifold 242B, exhausting through solenoid 243 and line 253A. Regulators 246A and 246B may be adjusted to apply more pressure to one edge of the work strip W to guide strip that is tracking imperfectly.

To provide for substantially complete enclosure, apart from the action of the seal rolls, between the internal protective atmosphere and external air at the entrance and exit seals, provision is made for separate closure gates, located inwardly of the seal rolls. With such gates, a good closure can be effected when it is desired to stop the strip travel for various reasons, including repair of

70

75

the roll seals. Reference, therefore, is made once more to FIGURES 1, 2 and 3 wherein is illustrated a closure gate including a lower housing member 170 attached to member 14 of the roll seal housing, an upper member 172 attached to the lower end flange 174 of the casing of a furnace F. Slots 176 and 178, in members 170 and 172, respectively, are in alignment with slot 18 of member 14 for passage of work strip W. Member 170 has a generally flat upper surface 180 terminating at ribs 182 which form channels for packing material 184.

A pair of metal gates 186 and 187, rest on top of packing inserts 184 which generally define a flat support plane, but which are sufficiently deformable to provide sealing action at contact with gates 186 and 187. The inboard edges of gates 186 and 187 are slotted at 188 to receive packing inserts 189 in opposed alignment one with the other. Gates 186 and 187 are movable in a horizontal plane toward and from the pass line of the work strip W, and are operably shiftable by a pair of screw shafts 190 and 192 having right and left hand threads respectively, and aligned at right angles to, and on opposite sides of, the pass line of the work strip W. These shafts are journaled in fittings 194 and 196 and have packing means 198 to prevent gas leakage around the shaft. The threaded portions of the shafts engage nuts 200 seated in receptacles 202 of gates 186 and 187. Shafts 190 and 192 are caused to rotate in unison by sprockets 204, one on each shaft, which mesh with a continuous chain 206. A hand wheel 208 may be mounted on at least one screw shaft. In the alternative, the shafts may be motor driven.

When gates 186 and 187 are closed, they are effectively sealed at their abutting edges against work strip W by means of packing inserts 189, and also beyond the edges of the work strip W by contact of said packing inserts 189. Packing inserts 184 seal against gates 186 and 187 at the plane of their lower surfaces. Thus there is very little leakage past gates 186 and 187 when closed, if the packings are in proper condition. With the gates closed, furnace operation may be suspended with small loss of protective atmosphere. Repairs and adjustments may be made when needed, to the various elements of the seal roll means outboard of the gates 186 and 187. In preparation for repair work upon the seal rolls, seal leaves, and associated parts, inert gas such as nitrogen may be admitted to the space below the closure gates 186 and 187 through suitable means such as inlet 210 (see FIGURE 3) from any source not shown.

In the embodiment of the invention shown in FIGURES 8 and 9, a modified form of closure gate has been found to be satisfactory. In this embodiment, a closure gate 211 is provided to the right of the seal rolls 136 and 138, and is suspended by a link 212 from a lever 214 near each side plate 134. Levers 214 are attached to rotatable shaft 216 which extends through one side plate 134 and has suitable packing to prevent gas leakage. Another lever 218 is attached to the piston rod of actuating cylinder 220 and to lever 214. Gate 211 has packing strip 222 in its lower edge suitably fitted in channel means provided for this purpose, and with a full downward stroke, this packing strip engages a packing strip 224 positioned in channels in a stationary still member 226, the contact occurring at a level slightly below the work strip pass line. With moderate tension, the work strip may be deflected as much as necessary without difficulty. The gate 211 has a smooth vertical surface to bear against a transverse packing strip 228 suitably positioned in a slotted packing retaining jamb plate 230. The gate 211 also bears against a vertical packing strip 232 also inserted in a slotted vertical portion of jamb plate 230. Pressure means, including pressure roller 234, bell crank 236 and spring 238 are located on each side to insure sealing contact between gate 211 and packing strips 224 and 228.

In operation of the invention, it is desired to apply only such force to the rolls toward the pass line of the work strip W that the elastomeric roll coatings are flattened enough to insure sealing on normally smooth strip, and to flatten such strip should it become somewhat curved transversely. In the event that an imperfection such as a splice or a damaged area reaches the seal rolls, the roll coverings are sufficiently yieldable to enable separation sufficiently to pass the imperfection and then promptly reclose with very little increase of total force exerted by the rolls. To improve tracking, greater roll pressure may be applied nearer to one edge of the work strip W than to the other edge.

Thus in reading the foregoing discussion and description of the invention taken in conjunction with the drawings, it will be understood that the subject invention is an improved means for sealing furnaces adapted for continuous thermal treatment of strip being introduced into one end of a furnace and leaving the opposite end without interruption of movement.

It is to be further understood, that whereas several embodiments of the invention have been described hereinabove, these embodiments are by way of example only and are not intended to be construed in a limiting sense. Other arrangements and modifications will occur to those skilled in the art upon reading this specification and the attached claims, and upon examination of the included drawings, said other arrangements and modifications being within the spirit and scope of the invention as claimed.

We claim:

1. In a furnace for continuous thermal treatment of metallic strip having an opening therein for passage of strip, the improvement in seal means to seal said strip and furnace at said opening and comprising: housing means secured to said furnace and surrounding said opening; a pair of rolls, each having shafts extending from opposite ends and mounted in side plates of said housing means transverse to and on opposite sides of the pass line of said strip; each side plate having means for receiving one of the oppositely extending shafts of the same one of said rolls to permit shifting of said one roll toward and away from said other roll; means to shift said one roll into and out of sealing contact with said strip; means to seal the ends of said rolls with the inwardly facing surfaces of said side plates, and means to seal the peripheries of said rolls with said housing.

2. The device set forth in claim 1, including gate means between said furnace and said seal means to seal said opening when said one roll is shifted away from said other roll.

3. The device set forth in claim 1, wherein the peripheries of said rolls have bonded thereto a uniform layer of resilient elastic substantially heat resistant material.

4. The device set forth in claim 1, wherein the said means to seal the peripheries of said rolls with said housing comprise: a pair of trunnion mounted leaves pivotally secured to straight side walls of said housing; curved rear wall portions of said housing adapted to maintain contact with the back edges of said leaves during limited pivotal movement thereof about said trunnions; packing means secured to the side and back edges of said leaves for rubbing contact with the straight side and curved rear wall portions of said housing; and facing material secured to the roll contacting faces of said leaves for rubbing contact with respective peripheries of said rolls.

5. The device set forth in claim 1, wherein the means to seal between the peripheries of said rolls and said housing comprises: a pair of resilient leaves, each secured in relative gastight sealed contact to the inner walls of said housing, and in biased tangential gastight contact with an adjacent roll.

6. The device set forth in claim 5, wherein said leaves are of spring temper steel, lined on their roll contact surfaces with soft fibrous material.

7. The device as set forth in claim 1, wherein said other

roll is journaled in said housing for rotation about a fixed axis; said roll shifting means including a pair of levers each pivotally fastened at one end to said furnace, connecting links each pivotally fastened at one end to the free end of one of said levers and at the opposite end to one of said shafts of said one roll; and motor means secured to said furnace and to each of said levers adapted to shift said one roll relative to said other roll.

8. The device set forth in claim 7, wherein said motor means includes a pair of motors each secured to one of said levers, and motor control means to selectively actuate each said motor to provide for different roll pressures at opposite ends of said rolls.

9. The device set forth in claim 1, wherein each of said side plates has additional means for receiving one of the oppositely extending shafts of said other roll to permit shifting of said other roll toward and away from said first roll; and a pair of roll journal means each shiftable mounted on one of said side plates and to receive said shafts therein and to permit said roll shafts to be shifted in said receiving means.

10. The device set forth in claim 9, including a pair of torque rods secured in parallel between the roll journal means and on opposite sides of the strip plane.

11. The device set forth in claim 9, including a pair of torque rods secured in parallel between the roll journal means on opposite sides of the rolls, one of said rods being yieldable to the application of torque thereto.

12. The device set forth in claim 9, including a pair of torque rods secured in parallel between the roll journal members on opposite sides of said rolls, one of said torque rods being substantially unyieldable to the application of torque applied thereto.

13. The device set forth in claim 9, including a pair of tubular torque rods secured in parallel between the roll journal members on opposite sides of said rolls, one of said torque rods being substantially unyieldable to the application of torque applied thereto.

14. The device set forth in claim 9, including a pair of torque rods secured in parallel between the roll journal members on opposite sides of said rolls, one of said torque rods being tubular and relatively unyieldable to the application of torque applied thereto, and the other torque rod being solid and yieldable to the application of torque thereto.

15. The device set forth in claim 9, wherein each said roll journal means includes a shiftable plate pivotally secured at its lower portion to a side plate; plate shifting means; and connecting means pivotally secured to the upper portion of said shiftable plate and to said plate shifting means, whereby shiftable movement is imparted to a roll upon actuation of said shifting means.

16. The device set forth in claim 9, including motor means; slide means shiftable by said motor means; roll journal means each comprising a toggle plate pivotally secured at its lower portion to a side plate; toggle links pivotally connecting said toggle plates to said slide, whereby selective shifting of said slide by said motor means moves said pair of rolls toward and away from each other.

17. The device set forth in claim 9, wherein said roll journal means each comprise a bell crank pivotally secured to a side plate; one arm of said bell crank being secured to a roll shaft; and bell crank shifting means secured to the other arm of said bell crank to shift said bell crank about its pivotal axis.

18. The device set forth in claim 9, wherein said roll journal means comprise a pair of bell cranks pivotally secured to each side plate; one arm of each bell crank being secured to a roll shaft; bell crank shifting means secured to at least one of said bell cranks; and sector gears formed on the heels of said bell cranks for meshing engagement, whereby shifting of one bell crank about its pivotal axis will cause the other bell crank to shift in an equal and opposite direction about its pivotal axis.

19. The device set forth in claim 9, wherein said roll journal means comprise a pair of bell crank members pivotally secured to each side plate; one arm of each bell crank being secured to a roll shaft; bell crank shifting means secured to each of said bell cranks; a relatively rigid torque rod interconnecting corresponding bell cranks on opposite sides of a roll; a torque rod yieldable to torque applied thereto interconnecting corresponding bell cranks on opposite sides of the other of said rolls; and means to actuate said shifting means to selectively provide for different roll pressures at opposite ends thereof.

20. The device set forth in claim 9, wherein said roll end seal means comprises a compressible washer having a center opening adapted to fit snugly about the roll shaft, said washer being of substantially the same outer diameter as its adjacent roll; a rigid washer positioned between said compressible washer and one of said side plates and having a center opening provided with a running fit on said roll shaft, each said shaft receiving means being covered by one of said washers and being of a length to provide total movement of said roll shaft therein without breaking the seal between said plate and said washer.

21. The device set forth in claim 9, wherein said roll end seal means comprises a compressible washer having a center hole adapted to fit snugly about the roll shaft, said washer being of substantially the same outer diameter as the outer diameter of said roll and being adjacent thereto; a plastic washer adjacent said compressible washer having a center hole provided with a running fit on said roll shaft and being in outer diameter slightly less than the outer diameter of said compressible washer; and a rigid wear resistant washer having a running fit with said roll stub shaft and being substantially the same diameter as said plastic washer, and being positioned between said plastic washer and one of said side plates.

22. The device set forth in claim 21, wherein the distance between said side plates is selected to compress each compressible washer to substantially one-half of its free thickness when at least one of said other washers is in place between said compressible washer and one of said side plates.

23. The device as set forth in claim 9, including means for yieldingly maintaining said rolls generally parallel while permitting sufficient variations therefrom to accommodate desired variations in roll pressure distribution.
